UNITED STATES PATENT OFFICE.

PETER A. SNYDER, OF JERSEY CITY, NEW JERSEY.

DESIGN FOR A HASP-LOCK CASE.

SPECIFICATION forming part of Design No. 14,434, dated November 20, 1883.

Application filed September 14, 1883. Term of patent 7 years.

To all whom it may concern:

Be it known that I, PETER A. SNYDER, of Jersey City, in the county of Hudson and State of New Jersey, have invented a new and 5 useful Design for Hasp-Locks, of which the following is a specification.

In the accompanying drawings, forming part of this specification, Figure 1 illustrates a top view of a newly-designed lock-case. Fig. 2 is 10 a side elevation, and Fig. 3 is a bottom view, of the same.

The leading features of my newly-designed case are the raised hood portion A, which is located on the front end and top of the case, 15 and extends from one side of the case to the other, and presents a convex or crowned appearance, and the extended eye portion, which extends from the circular end of the case, and is substantially the same as illustrated.

Having thus described my newly-designed 20 lock-case, what I claim is—

The design for a hasp-lock case, herein described and illustrated, the same consisting of a case provided with a raised hood portion on a square front end, and a circular back end to 25 the case, from which extends a bar eye portion, as illustrated and specified.

In testimony that I claim the foregoing design for hasp-locks, as above described, I have hereunto set my hand this 21st day of July, 30 1883.

PETER A. SNYDER.
